UNITED STATES PATENT OFFICE.

CHARLES ANDERSON, OF SOUTH BEND, INDIANA, ASSIGNOR TO THE SOUTH BEND IRON WORKS, OF SAME PLACE.

REVERSIBLE MOLD-BOARD PLOW.

SPECIFICATION forming part of Letters Patent No. 424,400, dated March 25, 1890.

Application filed December 14, 1889. Serial No. 333,765. (No model.)

To all whom it may concern:

Be it known that I, CHARLES ANDERSON, of South Bend, in the county of St. Joseph and State of Indiana, have invented certain new and useful Improvements in Reversible Mold-Board Plows; and I do hereby declare the following to be a full, clear, and exact description of the invention, such as will enable others skilled in the art to which it appertains to make and use the same.

My invention relates to an improvement in reversible mold-board plows, the object being to provide a plow of this type employing few and simple parts so arranged that they may all be shifted by means of levers or similar devices from the rear of the plow.

Further objects are to provide improved means for reversing the mold-board and colter or jointer and for swinging the beam laterally upon its pivot.

With these ends in view my invention consists in a reversible mold-board and standard to which the mold-board is pivoted in connection with a reversible colter.

It further consists in a reversible mold-board, a reversible colter, and a standard upon which these parts are pivotally supported, in combination with a swinging beam, levers for reversing the colter and swinging the beam, and a spring-actuated latch for locking the mold-board in position on either side of the standard.

It still further consists in certain novel features of construction and combinations of parts, as will be hereinafter described, and pointed out in the claims.

In the accompanying drawings, Figure 1 is a view in perspective of my improved plow. Fig. 2 is a vertical sectional view. Fig. 3 is a rear elevation; and Figs. 4, 5, 6, and 7 are detail views.

A represents the standard of the plow, which consists of a substantially triangular frame comprising the upwardly-diverging arms 1 and 2 and the reach-plate 3, extending across from one arm to the other and integral with both. The lower end of the standard where the diverging arms 1 and 2 join each other is extended forward and backward for a short distance to form a shoe 4 and furnished at the extreme ends with the bearing-pintles

5 5. The shoe has a runner 6 fitted to it, and web 7 across the forward end of the runner has a hole 8 therein, which receives the forwardly-projecting pintle 5, and at the rear end the runner is held on the shoe by means of the bolt 9 and nut 10 or by similar devices.

B is the reversible mold-board. It is essentially the same as other mold-boards for similar purposes, being symmetrically formed on both edges, so that one will cut the sod with as much facility as the other, or turn it over as completely as the other. The mold-board is re-enforced on its inner side with a plate 11, and in the forward end of the latter a socket 12 is formed for the forward pintle 5, and the rear end of the mold-board is provided with an inwardly-projecting bracket-arm 14, which has a bearing 15 in its outer end to receive the rearwardly-projecting pintle 5. A brace-rod 17, passing through a lug on the re-enforcing-plate 11, also passes through a hole 18 in the bracket-arm 14 and has nuts on its ends by which to hold the arm 14 at the required distance to retain the pintles 5 in their bearing-sockets 12 and 15. When thus retained in the relative positions named, the mold-board is in position to swing to either side of the standard.

To lock the mold-board in one of these two positions a double hook-latch 19 is pivotally supported on the rear edge of the arm 2 of the standard. A hole 20, of two different bores, is made in this arm, and a pin or bolt 21, passing through the hole, serves as a support for the latch. A small spiral spring 22 encircles the portion of the pin or bolt in the portion of the hole of larger bore, and a sleeve 23 and nut 24 are then placed on the bolt, the nut being turned to regulate the tension of the spring to make it act with more or less power upon the double-hooked latch. Immediately above and below the support the latch is provided on its inner face with rounded or convex bearing-projections 25 and 26, which impinge upon the rear edge of the arm 2, which, in combination with the tensile action of the spring 22, make the latch turn automatically after it has been moved beyond the centers of the bearings. The hooks of the latch engage the edges of the bracket-arm 14 on one side or the other, according to the way the

mold-board is turned. Foot-rests 27 27 are formed back of the hooks, upon one of which the driver places his foot in order to disengage one hook from the arm 14, and after the 5 latch passes its center the other hook will automatically engage the other side of the arm 14. If the latch is changed before the mold-board turns, the slanting edge 13 of the bracket-arm engaged by the hook, will, by its 10 contact with the inclining lower edge of the hook, force the latter back until it locks the arm, where it will remain until again rocked and the mold-board is to be again reversed. The mold-board is kept from turning over too 15 far by striking the arm 1 of the standard and the latch holds the mold-board against the standard, and a stop 28 on the rear of arm 2 prevents the latch from turning over beyond that point.

20 The handles 30 30 of the plow are bolted or otherwise secured at their lower ends to the arm 2 of the standard, and these handles are held apart the required distance by the spacing-bars 31 and 32, to be hereinafter referred to.

C indicates the beam of the plow. The rear end of this beam is fitted into and secured to a casting 33, which forms a rear extension of the beam. The extension bears upon the 30 reach-bar at the forward and rear end. At the forward end it is pivoted by means of a bolt 34 and at the rear end it is provided with a bolt 35, which extends into the transverse elongated slot 36 in the rear end of the reach-bar. The object of this slot is to allow a limited 35 lateral movement of the beam, and the beam is swung by means of a lever 36', fulcrumed on the lower spacing-bar 31. The lever is provided with a rounded elliptical slot or loop 40 38 at its lower end, which loosely receives a round projection 39 on the rear end of the extension and allows a free movement of the latter therein when the lever is swung in either direction. The lever terminates in a 45 handle 40 at its outer end, by which it is manipulated, and a tooth 41 on the back of the lever is adapted to enter one of the notches 42 42 on the curved spacing-bar 32, by which it is locked in position. To swing the beam 50 this lever is simply swung to the right or left. The colter or jointer 43 is also reversible, and to this end is secured on the end of the rod 44. Said rod extends obliquely through a bearing 45, formed for it in the arm 1 of the standard 55 and loosely through the transverse slot 46 in the casting or extension just back of the beam. An adjustable loop 47 for regulating the depth of cut of the colter is sleeved onto the end of the rod and held rigidly thereto by 60 means of a set-screw 48, and a flexible lever 49, pivoted on the bolt 35, extends back loosely through this loop, and at its rear end is furnished with a handle 50, which extends nearly to the handles of the plow, where it 65 may be easily grasped by the plowman. The loop is provided in the middle with a lug 51, over which the lever has to be thrown in order

to reverse the colter. The lug prevents the colter from jolting over accidentally, as it would be inclined to do if the lever were permitted to move freely to the other side of the loop. Again, the loop, by projecting forward a short distance, acts as a lever, so that when the hand-lever presses against its outer or upper end it readily swings the rod and attached 70 colter, whereas to merely swing the hand-lever across the loop, if the lug were dispensed with, would not have this effect. A portion of the loop lies in the slot 46, and thus prevents the 75 rod from moving endwise.

80 It is evident that slight changes might be resorted to in the form and arrangement of the several parts described without departing from the spirit and scope of my invention, and hence I do not wish to limit myself to the 85 exact construction herein set forth; but,

Having fully described my invention, what I claim as new, and desire to secure by Letters Patent, is—

1. The combination, with a standard, a rod 90 having a bearing in said standard, and a colter secured to the rod, of a loop secured to the rod, and a hand-lever passing through the loop and adapted to swing the loop, rod, and colter, substantially as set forth.

95 2. The combination, with a standard, a reversible colter, and a rod having a bearing in the standard and to which the colter is secured, of a loop secured to the end of the bolt, said loop having a lug projecting into it, and a hand-lever pivoted on the standard and extending through the loop, for the purpose described.

100 3. The combination, with a standard and a beam pivoted thereto, said beam having a slotted rear end, of a rod loosely mounted in a bearing in the standard and having a colter on one end and a loop on the other end, the collar of which extends loosely in the slot in the beam, and a hand-lever pivoted over the 105 beam and passing loosely through the loop, whereby the bolt and colter are shifted with each swing of the hand-lever, substantially as set forth.

110 4. The combination, with a standard, handles secured thereto, and spacing-bars between the handles, of a beam pivoted to the standard, said beam having a projection on the rear end, and a hand-lever fulcrumed on the lower spacing-bar and having a loop in which the projection rests loosely, said lever having a tooth adapted to enter notches in the upper spacing-bar, substantially as set forth.

115 5. The combination, with a standard having a transverse elongated slot in its upper rear portion, a beam pivoted on the standard, and a bolt in its rear end which extends loosely into the transverse slot to limit the lateral swings of the beam, of a reversible 120 colter, the stem of which passes through the standard and beam, and levers for moving the colter and swinging the beam, substantially as set forth.

6. The combination, with the standard and a reversible mold-board, of a double-hooked spring-actuated latch for engaging the mold-board and locking it on either side of the standard, and convex or rounded bearings on the latch adapted to impinge against the edge of the standard and by their contact automatically swing the latch when it has passed its center, substantially as set forth.
7. The combination, with a standard, of a reversible mold-board pivoted thereto, a double-hooked latch for locking the mold-board, a pin or bolt upon which the latch is pivoted, a spring on this pin, a nut for regulating the tension of the spring, and a sliding sleeve on the pin interposed between the spring and nut, substantially as set forth.
8. The combination, with a standard, of a mold-board having a socket on one side and a bracket-arm having a bearing in one end and inclines on the edges, the socket and bearing adapted to receive pintles on the ends of the standard, and a pivoted spring-actuated double-hooked latch having inclines on its lower edges and rounded or convex bearings on each side of its center, substantially as set forth.
9. The combination, with a standard substantially triangular in form, comprising the arms 1 and 2 and the reach 3, and a beam 30 pivoted on the standard at the forward end and having a bolt in the rear end which extends into the transverse slot in the reach-bar, of a reversible mold-board, a spring-actuated double-hooked latch adapted to lock the mold-board, a reversible colter, and levers for swinging the colter and beam and for locking them, substantially as set forth.
- In testimony whereof I have signed this specification in the presence of two subscribing witnesses.

CHARLES ANDERSON.
